UNITED STATES PATENT OFFICE.

ALLISON H. FLEMING, OF FAIRMONT, WEST VIRGINIA, ASSIGNOR TO FLEMING SALES CO., OF FAIRMONT, WEST VIRGINIA, A CORPORATION OF WEST VIRGINIA.

RAZOR-BLADE CLAMP.

941,566.

Specification of Letters Patent. Patented Nov. 30, 1909.

Application filed September 7, 1909. Serial No. 516,380.

To all whom it may concern:

Be it known that I, ALLISON H. FLEMING, a citizen of the United States, residing at Fairmont, in the county of Marion and State 5 of West Virginia, have invented a new and useful Razor-Blade Clamp, of which the following is a specification.

This invention has reference to improvements in holders for safety razor blades and 10 its object is to provide a holder for such type of razor blades whereby the blades may be honed or stropped the holder being such as to present the edge of the blade at the proper angle to the sharpening surface.

15 The holder is designed to be used in connection with any suitable form of stropping machine and to provide a holder which may be used interchangeably with different types 20 of safety razor blades whether of the double edge or reinforced style whereby the blades are firmly held without the necessity of special fastening devices.

The invention will be best understood 25 from a consideration of the following detail description taken in connection with the accompanying drawings forming a part of this specification in which drawings,

Figure 1 is a view of the improved holder 30 as struck up from a piece of sheet metal and before being folded upon itself to complete the holder. Fig. 2 is a cross section through the holder showing a safety razor blade in place. Fig. 3 is a perspective view 35 as seen from the bottom or tongue side of the holder. Fig. 4 is an enlarged view of one of the spring tongues for locking the blade in place in the holder. Fig. 5 is an enlarged section on the line A—B of Fig. 4.

Referring to the drawings there is shown 40 in Fig. 1 a holder 1 constructed in accordance with the present invention and before being folded on itself to form two opposed elastic members 2—3 designed to clasp and hold the razor blades, one of which latter 45 is shown at 4 in Fig. 2, the razor blade shown being of a known double edge type with spaced perforations 5 extending therethrough. The member 2 of the holder has spaced perforations 6 designed to match the 50 perforations 5 of the blade 4 and at an intermediate point this holder is formed with a longitudinal slit 7 designed to impart elasticity to the holder when the members 2 and 3 are folded together. These parts however 55 form no part of the present invention.

In the member 3 of the holder 1 there are formed two elastic tongues 8 projecting in opposite directions one from the other and terminating in heads 9 struck up from one side to form rounded bosses 10, these bosses 60 projecting from the plane of the tongues 8 on the face matching the perforations 6 in the member 2 when the parts are folded together so that these bosses may enter the perforations 6 to a limited extent. Each 65 tongue 8 is struck out from the metal of the member 3 of the holder leaving a slot 11 conforming in shape to the tongue, between the tongue and the body of the member 3. Where the tongue joins the body of the member 3, the tongue being integral therewith, the elasticity of the tongue may be augmented by reducing its width by expanding the width of the slot as shown at 12 or in any other manner. This increase in the elasticity of the tongue 8 is not mandatory and the tongues may be of the same diameter throughout from the head 9 to the point where the tongues merge into the body of the member 3. Since the heads 9 are nearer 70 to the outer ends of the holder than they are to each other and in order to make the tongues 8 long enough to render them quite elastic, these tongues extend one toward the other and their points of junction with the body portion of the member 3 are contiguous. The tongues 8 have a normal tendency 75 toward the member 2 so that the projecting portions of the bosses 10 may extend into the perforations 6.

When the two members of the holder 1 are folded one toward the other, their inner faces are in close relation so as to engage the opposite faces of the wafer like blades employed in various types of safety razors and 95 this is especially true when the holder is mounted in the stropping device to which it is adapted. Under such circumstances the normal elasticity of the spring fingers 8 will cause the bosses 10 to extend through the 100 perforations 5 in the blades 4 and enter the perforations 6 thus effectually locking the blade in the holder.

There are numerous types of safety razor blades which are not provided with spaced 105 perforations and it is customary to provide stropping machines for safety razor blades with special holders adapted to the different types of blades. The holder however of the present invention will take various types of 110

blades, including those with reinforced backs, without interference. This is due to the fact that the projecting members of bosses 10 are formed on the free ends of 5 elastic fingers so that these bosses will spring into the perforations in the blade when present and so lock the blade in place, or will yield to the insertion of an unperforated blade and when the holder is placed in the 10 stropping machine the blade will be held by these yielding bosses frictionally and be thereby gripped against accidental displacement.

The yielding character of the bosses or 15 projections designed to enter the perforations of blades to hold them in the device makes the holder equally adapted for unperforated blades so that a single holder may be used for various types of blades thus 20 avoiding the necessity of providing a separate holder for different types or groups of blades on the market.

What is claimed is:

1. A safety razor blade holder for carrying 25 the blade during stropping, having opposed members adapted to grasp the razor blade, one of said members being provided with bosses or projections extending toward the other member and yieldable independently of the member carrying them.

2. A safety razor blade holder for carrying 30 the blade during stropping, having opposed members adapted to grasp the razor blade, one of said members being provided

with spring fingers having at their free ends 35 bosses or projections directed toward the other member and spaced to enter perforations in perforated types of safety razor blades.

3. A holder for safety razor blades during 40 stropping having opposed members adapted to grasp the razor blade, one of said members having formed therein elastic fingers terminating in projections or bosses directed toward the other member,

4. A holder for safety razor blades during 45 stropping having opposed members adapted to grasp the razor blade, one of said members having formed therein alined elastic fingers with their free ends remote one from 50 the other and terminating in projections or bosses directed toward the other member.

5. A sheet metal holder for safety razor blades during stropping comprising a single piece of sheet metal bent on itself to form 55 opposed blade grasping members, one of which members has spring fingers formed therein with their free ends remote one from the other and terminating in struck up portions or projections extending toward the 60 other member.

In testimony that I claim the foregoing as my own, I have hereto affixed my signature in the presence of two witnesses.

ALLISON H. FLEMING.
